Primary Examiner — Janice Hallmark(74) *Attorney, Agent, or Firm* — McGarry Bair PC(57) **CLAIM**

The ornamental design for a ceiling fan, as shown and described.

DESCRIPTION

FIG. 1 is a bottom perspective view of a ceiling fan, showing my new design;

FIG. 2 is a top perspective view thereof;

FIG. 3 is a top view thereof;

FIG. 4 is a bottom view thereof;

FIG. 5 is a front view thereof;

FIG. 6 is a side view thereof;

FIG. 7 is another side view thereof; and,

FIG. 8 is a rear view thereof.

Portions of the ceiling fan shown in broken lines forms no part of the claimed design.

The break lines on the ceiling fan's blades depict a symbolic break in length and form no part of the claimed design.
